CLAIM

The ornamental design for an extendable plant stake, as shown and described.

DESCRIPTION

FIG. 1 is a perspective view of an extendable plant stake, showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a left side view showing the extendable plant stake, in folded state.

1 Claim, 7 Drawing Sheets
